DESIGN FOR A KNITTED CURTAIN FABRIC

Reuben Lubarsky, New York, N. Y., and Frank Smizaski, Jersey City, N. J., assignors to Ace Novelty Products Corporation, Newark, N. J., a corporation of New Jersey

Application January 19, 1940, Serial No. 89,592

Term of patent 7 years

To all whom it may concern:

Be it known that we, Reuben Lubarsky and Frank Smizaski, both citizens of the United States, residing respectively at New York city, in the county of Kings and State of New York, and at Jersey City, in the county of Hudson and State of New Jersey, have invented a new, original, and ornamental Design for a Knitted Curtain Fabric, of which the following is a specification, reference being had to the accompanying drawing, forming part thereof.

The figure is a plan view of a knitted curtain fabric, showing our new design.

We claim:

The ornamental design for a knitted curtain fabric, substantially as shown.

REUBEN LUBARSKY.
FRANK SMIZASKI.
